United States Patent Office

Des. 181,510

Patented Nov. 19, 1957

181,510

WINDOW SHADE OR SIMILAR ARTICLE

Max Wolkowitz, New York, N. Y., assignor to Bell Bed-spreads, Inc., New York, N. Y., a corporation of New York

Application December 31, 1956, Serial No. 44,371

Term of patent 14 years

(Cl. D21—6)

Fig. 1.

Fig. 2.

Des. 181,510

PAGE 2

Fig. 3.

Fig. 4.

Fig. 5

Fig. 1 is a fragmentary front view of a window shade showing my new design and illustrating the top portion thereof;

Fig. 2 is a front view of the window shade as it appears partially unrolled and with portions thereof being shown broken away for convenience of illustration;

Fig. 3 is an enlarged fragmentary front view of the window shade shown in Fig. 2;

Fig. 4 is a side view of the window shade with portions thereof being shown broken away for convenience of illustration; and

Fig. 5 is a rear view thereof as it appears in partially rolled-up position.

I claim:

The ornamental design for a window shade or similar article, as shown.
